UNITED STATES PATENT OFFICE

EDWIN B. STIMPSON, OF BROOKLYN, NEW YORK, ASSIGNOR TO EDWIN B. STIMPSON COMPANY, OF BROOKLYN, NEW YORK, A CORPORATION OF NEW YORK

RIVETING MACHINE

Original application filed February 25, 1928, Serial No. 257,013. Divided and this application filed November 10, 1928. Serial No. 318,518.

This invention relates to rivet setting machines, and has for its object to increase the field of application for such machines and to facilitate their operation with large or cumbersome articles requiring considerable clearance below the anvil and on substantially all sides thereof.

This application is a division of my application Serial No. 257,013, filed February 25, 1928, and in distinction from the embodiment specifically claimed therein, in the present species of the invention the means supporting the anvil from the head of the rivet setting mechanism includes a bracket slightly offset laterally therefrom and having a relatively long, vertically depending portion, and a relatively short, horizontal arm at the lower end thereof, on which the anvil is directly mounted.

20 In the drawings:

Fig. 1 is a side elevation of one specific embodiment.

Fig. 2 is a front elevation.

25 Fig. 3 is a perspective detail of the supporting bracket and arm.

An ordinary standard 10 is surrounded by a usual head 11 carrying the customary rivet feeding mechanism 13 and rivet setting mechanism 12. A usual form of anvil 30 is provided for cooperation with the mechanism 12. As shown in Figs. 1 and 2 the anvil is supported from the head 11 by means of a bracket 28, Fig. 3, which includes a short horizontal arm 28^a and also a relatively long, downwardly depending arm 28^b, which are usually integrally formed.

The bracket 28 may be secured to the head 11 in the manner shown in the parent application, above identified; but in the present 40 specific form, and in contrast with the other forms shown in said parent application, the bracket is much smaller, and is provided with a relatively short lateral arm 29 supporting 45 the anvil 30, and the vertical arm of the bracket is longer than either of its lateral arms; this form of the invention is useful where little clearance is necessary on one side of the anvil but a large amount is needed below the 50 anvil, on all sides, or substantially so.

I claim:

1. The combination with a rivet setting machine, of a supporting head therefor, an anvil, said head comprising a member projecting laterally above said anvil, and supporting means for said anvil secured to said member, and including a long vertical arm and short horizontal arms, to one of which the anvil is connected. 55

2. The combination with a rivet setting 60 mechanism, of a supporting head therefor, a standard carrying said head and mechanism, an anvil, and supporting means for said anvil extending laterally a short distance from said head and vertically downward a much greater 65 distance, said means comprising a short lateral arm extending to a position below said anvil.

In testimony whereof I affix my signature.

EDWIN B. STIMPSON. 70
